COFFEE MAKER

Achille Decarli, Via Carlo Poerio 2/a, Milan, Italy

Filed Mar. 27, 1962, Ser. No. 69,454

Term of patent 7 years

(Cl. D2—3)

FIG. 1.

FIG. 2.

FIG. 4.

FIG. 3.

FIG. 1 is a top plan view of a coffee maker embodying my new design;

FIG. 2 is a front elevational view thereof;

FIG. 3 is an elevational view of one side thereof; and

FIG. 4 is a perspective view of the rear and opposite side thereof.

I claim:

The ornamental design for a coffee maker, substantially as shown.
